UNITED STATES PATENT OFFICE

THOMAS S. GORTON, JR., OF CHICAGO, ILLINOIS

DESIGN FOR A CONTAINER

Application filed November 25, 1932. Serial No. 46,147. Term of patent 14 years.

To all whom it may concern:

Be it known that I, THOMAS S. GORTON, Jr., a citizen of the United States, residing at Chicago, in the county of Cook and State of Illinois, have invented a new, original, and ornamental Design for a Container, of which the following is a specification, reference being had to the accompanying drawing, forming part thereof.

Fig. 1 is a side elevation of the container;

Fig. 2 is a plan view; and

Fig. 3 is a front end elevation of the container.

I claim:

The ornamental design for a container, as shown.
